[57] CLAIM

The ornamental design for a picture hanging aid, or similar article, substantially as shown and described.

DESCRIPTION

FIG. 1 is a front isometric view of a picture hanging aid, or similar article, showing my new design.

FIG. 2 is a rear isometric view thereof.

FIG. 3 is an enlarged side elevational view of the picture hanging aid, or similar article, the opposite side elevational view being a mirror image thereof.

FIG. 4 is a front elevational view thereof.

FIG. 5 is a rear elevational view thereof.

FIG. 6 is a top plan view of FIG. 4.

FIG. 7 is a bottom plan view of FIG. 4.

FIG. 1.

FIG. 2.

FIG. 3.

FIG. 4.

FIG. 5.

FIG. 6.

FIG. 7.
